PROTECTIVE SHIELD FOR SHOES

Henry K. Linenkohl, Augusta, Ga.

Application December 7, 1954, Serial No. 473,657

1 Claim. (Cl. 36—72)

The present invention relates to new and useful improvements in shields or masks particularly for but not necessarily restricted to children's white shoes and has for its primary object to provide, in a manner as herein-after set forth, an article of this character comprising a novel construction and arrangement whereby the upper may be expeditiously polished without soiling the welt, sole and heel.

Another very important object of the invention is to provide a polish shield of the aforementioned character comprising novel securing means whereby the device may be correctly and snugly fitted to shoes of various shapes, widths and lengths.

Other objects of the invention are to provide a protective shield of the character described for shoes which will be comparatively simple in construction, strong, durable, highly efficient and reliable in use and which may be manufactured at low cost.

All of the foregoing and still further objects and advantages of the invention will become apparent from a study of the following specification, taken in connection with the accompanying drawing, wherein like characters of reference designate corresponding parts throughout the several views, and wherein:

Figure 1 is a bottom perspective view, showing a shield constructed in accordance with the present invention applied to a shoe.

Figure 2 is a top perspective view of the device.

Figure 3 is a cross-sectional view.

Figure 4 is a detail view in perspective of one of the ductile or bendable metallic securing clamps after it has been bent to shape.

Referring now to the drawing in detail, it will be seen that the embodiment of the invention which has been illustrated comprises an elongated band of thin, elastic rubber or other suitable material which is designated generally by reference character 5, which band may be of any desired dimensions. The band 5, which is normally flat, has its marginal portions rolled in a manner to provide integral beads 6. The band 5 is adapted to be stretched around the usual bottom 7 of a conventional baby shoe 8 in a manner to fully enclose and mask the marginal portions of the sole, the heel and the welt thereof. After being thus applied, the band 5 is substantially U-shaped in cross-section, as illustrated to advantage in Figure 3 of the drawing.

Traversing the band 5 at an intermediate point and having its end portions overlying same and vulcanized or otherwise suitably secured beneath the lower portion

2

thereof is an elastic instep strap 9 which is also of thin rubber or other suitable resilient material. The elastic instep strap 9 is folded on itself and vulcanized in a manner to provide thickened or reinforced longitudinal marginal portions 10.

Embedded in the end portions of the marginal portions 10 of the elastic instep strap 9 are pairs of longitudinally spaced, flat, normally straight clamps 11 of suitable ductile or bendable metal. The ductile clamps 11 are adapted 10 to be bent in a manner to provide substantially J-shaped hooks for engagement over the edges of the shoe sole at the instep.

It is thought that the manner in which the shield is used will be readily apparent from a consideration of the foregoing. Briefly, the outer end portions of the normally straight, ductile outer clamps 11 are placed on top of the sole at the instep on the outer side of the shoe. These clamps are then bent downwardly and inwardly beneath the shoe and assume substantially the shape 20 shown in Figure 4 of the drawing. These clamps are then removed from the shoe and the procedure is repeated with the clamps on the inner side of said shoe. The elastic strap 9 is then stretched and the substantially J-shaped clamps or hooks 11 are engaged over the outer 25 and inner edges of the shoe at the instep. The elastic band 5 is then stretched and snapped under tension around the sole and heel of the shoe. The strap 9 is also under tension for causing the band 5 to follow the contour of the sole and heel and fit snugly thereon. The upper of 30 the shoe may now be rapidly cleaned and polished without soiling the welt, sole and heel of said shoe.

It is believed that the many advantages of a protective shield or mask constructed in accordance with the present invention will be readily understood and although a preferred embodiment of the device is as illustrated and described, it is to be understood that changes in the details of construction may be resorted to which will fall within the scope of the invention as claimed.

What is claimed as new is as follows:

40 A protective shoe shield of the character described comprising: an elongated elastic rubber band for enclosing the marginal portions of a shoe sole and heel, an elastic rubber shank strap traversing the band at an intermediate point and having its end portions overlying 45 said band and secured thereon, said strap including a central portion and marginal side portions, said side portions overlying said central portion and being secured thereon, and pairs of longitudinally spaced, ductile clamps 50 enclosed in said marginal side portions of the strap on the end portions of said strap and engageable around the edges of and over the sole for anchoring said strap thereto under tension.
